UNITED STATES PATENT OFFICE.

WALTER K. COOK, OF MINNEAPOLIS, MINNESOTA, ASSIGNOR TO THE AMERICAN BANK PROTECTION COMPANY, OF MINNEAPOLIS, MINNESOTA, A CORPORATION OF MINNESOTA.

ELECTRICAL BURGLAR-ALARM.

1,016,936.

Specification of Letters Patent. Patented Feb. 13, 1912.

Application filed August 9, 1909. Serial No. 512,082.

To all whom it may concern:

Be it known that I, WALTER K. COOK, a citizen of the United States, and resident of Minneapolis, Hennepin county, Minnesota, have invented certain new and useful Improvements in Electrical Burglar-Alarms, of which the following is a specification.

My invention relates particularly to that class of electrical burglar alarm systems which employ guarded structure, such as a bank-vault, connected by electric circuits with an alarm mechanism located in an isolated protected housing, as distinguished from those systems in which the alarm mechanism is located at a central station where it is under the care or observation of a watchman. A system of the class to which my invention belongs is shown in the patent to Clyde Coleman, Reissue No. 11,626, dated August 17, 1897.

The object of my invention is to provide a more efficient system than any yet devised and one that cannot be tampered with in any way without sounding an alarm.

To this end my invention consists generally in the constructions and combinations hereinafter described and particularly pointed out in the claims.

The accompanying drawing, forming part of this specification is a diagrammatic view of a burglar alarm system embodying my invention.

In the drawing, A represents a bank-vault or guarded structure, and B a protected housing, preferably located at a distance from the guarded structure, and, in practice, usually arranged upon the outside wall of a bank building, which contains the guarded structure or vault. The protected housing, B, contains the main alarm. I usually employ, for this purpose, an electrically operated gong 1, which will, when operated, (if the housing is located on the outside of the bank building) arouse all the people in the neighborhood.

I have here shown the bank-vault or guarded structure provided with a suitable inclosing wall 2, which is provided with an inner metallic lining 3, and an outer metallic lining 4, these linings being separated from each other by a sheet of insulating material 5. If these metallic linings are electrically connected, or short-circuited, in any manner, an electric circuit will be completed and all

the alarms will be sounded as hereinafter described. I also prefer to provide upon the vault wall two alarm gongs 6 and 7, protected by shields 8 and 9 so arranged that any attempt to move the shields, or to penetrate them with a metallic instrument, will also close an electric circuit and sound all the alarms, as hereinafter described.

The arrangement of the gongs 6 and 7 on the outer wall of the vault, protected by the shields 8 and 9, is preferably that shown and described in the patent of Robinson and Green, No. 708,496, dated September 2, 1902.

I may also provide the vault with a protection for its door by electrical connections to the door 10 and an insulated lining 11 thereon; and by electrical connections to the combination lock spindle 12, and the sliding bolt frame 13. I may also provide a timer 14, by which the door protection is switched off at the beginning of business hours. Such mechanism, for these purposes, as I prefer to use is shown and described in the patents of Robinson and Jacoby, No. 771,748 and No. 771,749, both dated October 4, 1904. The vault vestibule is also preferably provided with linings 15 and 16 separated by an insulating sheet 17.

The guarded housing B is preferably in the form of a metallic box 18 having an insulated metallic lining 19, and a removable cover 20 held in place by screws 21 which also serve to engage contact springs 22 and hold them out of engagement with contact plates 23. If an effort is made to enter the housing by removing any one of the screws 21, a circuit will be closed and the alarms will be sounded.

I do not limit myself to the described form of barriers or circuit closers for the vault or guarded structure and protected housing, nor do I claim any novelty in these devices *per se*. Any well known form of electrical barriers or circuit closers that will, when electrically connected, complete an electric circuit, may be employed.

Within the vault, I preferably arrange three open circuit batteries 24, 25 and 26, and one closed circuit battery 27. For convenience I designate the open circuit batteries as the "upper battery," the "middle battery" and the "lower battery," respectively. I also preferably provide three automatic drops of circuit closers 29, 30 and

31 which I designate the "right-hand drop," the "middle drop" and the "left-hand drop" respectively. Each of these drops is provided with an electro-magnet which, when energized, attracts an armature 32 and releases a circuit-closing shutter 33. The construction of the automatic circuit closers or drops that I prefer to employ is shown in the patent to Robins No. 850,101, dated April 9, 1907.

10 The main alarm gong 1 is directly in circuit, by means of conductors 34, 35, 36, 37, 38, and 39 with the middle battery through the shutter or circuit closer 33 that is controlled by the middle drop 30.

15 A common wire or conductor 40 connects the three drops. Conductor 41, 42 leads from the outer vault lining to the upper battery 24, and conductor 42 also extends to 20 the right-hand shield and shield gong, and also to the draw bolt plate 13 on the vault door and is connected to the conductor 61, which is in turn connected to the lock spindle 12 and to the vault door 10, and through 25 said door or the frame of the vault, to the outer vestibule lining 16. Conductor 45 extends from the upper battery 24 to a small bell 50 within the vault and connects with conductor 46 leading to the shutter of the 30 right-hand drop and with conductor 48 leading to the bolt work of the vault door. From the lower battery, conductor 51 leads to the small gong 53 and, through conductor 52, to the shutter of the left-hand drop 31. The 35 bells 50 and 53 are designed as test bells and by means of connections on the door (not shown) the circuits may be closed through these bells at any time for testing the batteries without sounding a general alarm.

40 The preferred arrangement for operating the test bells is that shown and described in the Robins and Jacoby Patent No. 771,749, hereinbefore referred to. The left-hand shield and shield bell are connected primarily to the lower battery and left-hand drop through conductors 54, 55, 56, 57, 58 and 59. Conductor 60 connects the gong 53 with conductor 48. Conductors 61, 62, 63, 64, 65 and 66 bring the open circuit barriers 50 of the vestibule, door, door-lock, door-bolt and timer devices into circuit with the right-hand drop and upper battery. The circuit is traced from the carbon side of the upper battery through the extension toward 55 the left of conductor 42, then through the draw bolt plate 13, or through the lock spindle 12, or through the door 10, or through the outer vestibule lining 16, and then from either one of these parts through 60 any short circuiting device to the opposite connection insulated therefrom. If the circuit has been closed by moving the draw bolt or manipulating the lock spindle, the current passes from the draw bolt plate 13, or 65 the spindle 12, through such insulated part

to the conductors 62, and 63, thence through the timer 14 to the conductor 66, thence through the conductor 67 and the conductor 44 to the coil of the right hand drop 29, thence through the shutter 33 of said drop 70 to the conductor 45 to the zinc side of the battery 24. If the short circuit is made by connecting the door 10 with the lining 11, or by connecting the lining 16 with the lining 15, the circuit is traced from said lining 75 11 or 15 through the conductor 64 to the conductor 65, from the conductor 65 through the timer 14, to the conductor 66 and thence as before through the coils and shutter of the right hand drop to the zinc side of the 80 battery 24. Conductors 44 and 54 are connected by a conductor 67. The casing of the outside or protected housing B, is connected to the upper battery 24, through the right-hand drop 29, by means of conductors 42 85 and 69', the covering 69 of the outside cable, outside casing 18, and lining 19, conductors 68, 67, 44, and coils 29, shutter 33 and conductors 46 and 45. If a short circuit is formed by connecting the casing 18 and the 90 lining 19, or by connecting the covering 69 and the conductor 68, the drops 29, 30 and 31 will be operated and a general alarm will be sounded.

95 The main outside gong 1 is directly in circuit with the middle battery through the shutter of the middle drop by means of conductors 34, 35, 36, 37, 38 and 39.

From the closed circuit battery 27, located in the vault, conductors 70 and 71 extend to 100 the electro-magnet or relay 72 in the protected housing B. The circuit, through the magnet 72, is normally closed, and the armature 73 is held normally out of engagement with the contact point 81. Should 105 this closed circuit be cut or broken in any manner, the armature 73 will be released and will move against the contact point 81 and will close a local trip circuit from the battery 74, conductor 75, armature 73, conductor 82, coils of magnet 77 and conductor 76 back to battery. The relay magnet 77 will be energized and will attract the armature 78. This will release the shutter 79 which will drop into contact with the contact point 83 and a local ringing circuit will now be closed from the battery 74 through conductor 76, conductor 80, shutter 79, conductor 89, the coils of the gong magnet, conductor 84, and conductor 75 back to the battery. When this local ringing circuit is closed, the gong 1 will begin to ring and will continue until the local ringing circuit is broken. When the closed circuit has been restored to its normal condition and the armature 73 drawn against the magnet 72, the local ringing circuit may be broken and the parts restored to normal position by a person in the vault or guarded housing. For 115 this purpose I provide a push-button 84 lo- 120 125 130

cated in the vault and having one of its contact pieces electrically connected to the conductor 37. The other contact piece of the push-button is connected to a conductor 85 which extends to an electro-magnet 86 for which the shutter 79 forms an armature. A conductor 87 connects the coils of this magnet with the conductor 36 leading to the middle battery. By operating the push-button 84 a circuit is closed through the magnet 86 energizing the same and raising the shutter 79 and breaking the local ringing circuit. The shutter is engaged and held in its elevated position by the armature 78.

Operation: When this apparatus is installed, ready for use, the vault or guarded structure A is completely surrounded by the double lining consisting of the metal sheets 3 and 4, separated from each other by the insulating material 5. Each of the sheets 3 and 4 forms a part of an open electric circuit, which is closed whenever the sheets are brought in contact with each other, or when a metallic instrument is brought in contact with both of said sheets, as would occur in drilling or cutting through the vault. Open, electric circuit connections are also provided on the shield 8 and its connections, on the door 10, on the combination lock members, and on all other parts of the vault which might be manipulated in an effort to enter it. The guarded housing B, which contains the main alarm gong, is preferably located at a considerable distance from the vault, and the conductors extending from the vault or guarded structure A to the guarded housing B, are arranged in a suitable cable and preferably inclosed by a cable covering 69. When any one of the open, electric circuits is closed, one of the drops 29 or 31 is operated and the corresponding shutter 33, is released and in dropping closes the electric circuit through the battery, which remains closed until the shutter is restored to normal position by a person entering the vault and manually raising the shutter. Whenever one of the automatic drops 29 or 31 is operated, the magnet of the middle drop 30 is also energized, the path of the current being from either one of said drops 29 or 31 through the conductor 40, and back through the conductors 68, 67, and either one of the conductors connected to said conductor 67. When the coils of the drop 30 are energized the shutter 33 falls and this closes the main ringing circuit from the middle battery through the magnet of the gong 1 in the protected housing. This gong will continue to ring until the vault has been opened and the shutter 33 has been manually restored to its normal position, thus breaking the ringing circuit. The circuits from the several barriers of the vault or protected struc-

ture may be readily traced; for instance, assuming that the electric circuit is closed by bringing into electrical contact the inner and outer linings 3 and 4, which may be done in a number of ways, as by drilling 70 or cutting the lining, the circuit will be closed from the upper battery 24 through the conductors 42 and 41, to the outer lining 4, then through the connecting instrument to the inner lining 3, then through the inner lining 3, then through the conductor 43 to the magnet of the drop 29, then through the shutter 33 and the conductor 45 to the other or zinc side of the upper battery 24. This circuit being completed the 75 shutter 33 will drop and engage the contact point connected with the conductor 47. The circuit will now be broken through the coils of the drop 29, but will be completed from the carbon side of the upper battery 24 80 through the conductor 42 to the frame of the right-hand gong 8 and back through the conductor 47, the shutter 33, and the conductor 46 to the other side of the battery 24. This will cause the right-hand gong 8 to ring from the upper battery 24 and this ringing will continue until the drop 33 is manually restored and the circuit last traced is broken. When the circuit is closed by connecting the lining 3 and 4, the circuit which energizes the coils of the drop 29 also energizes the coils of the drop 31 through the current flowing from the right-hand or carbon side of the battery 24 85 through the conductor 42, conductor 41, 100 lining 4, connection to lining 3, lining 3, conductor 43, conductor 67, conductor 54, magnet coils of drop 31, conductor 40, shutter 33 of drop 29, conductor 45, to the left-hand side of the battery 24. The coil 31 105 being energized, the shutter 33 will fall, engaging the contact point to said shutter which is connected to the conductor 57. The gong under the left-hand shield 9 will now be rung from the lower battery 26, the current passing as follows: from the right-hand or carbon side of the battery through the conductor 59, conductor 56, the gong within the shield 9, conductor 57, shutter 33, conductor 52, conductor 51, to the left-hand side of the battery 26. This gong will continue to ring until the shutter 33 is manually restored. In a similar manner, if any of the other barriers of the vault, or its door, or of the guarded housing are brought 110 in contact, one of the drops 29 or 31 will be energized, and instantly thereafter the other of said drops will be energized, as will also the central drop 30. The ringing circuits will then be completed, the main ringing circuit through the battery 25, one of the ringing circuits for one of the shield gongs through the upper battery 24; and the ringing circuit for the other shield gong 115 through the battery 26. These gongs will 120 125 130

continue to ring until the shutters 33 are manually restored and said ringing circuits are broken.

If the cable between the protected housing and the protected structure is severed so as to break the closed circuit from the battery 27 through the conductors 70, 71, to the magnet 72 in the outer or protected housing, the armature 73 will be released 10 and will be brought against the contact point 81. The local circuit will then be closed from the battery 74 in the outer housing as follows: through the conductor 75, the armature 73, the conductor 82, the coil 15 of the magnet 77 and the conductor 76, back to the battery 74. The coil 77 being energized will attract the armature 78 which holds up the armature or shutter 79. This shutter will then engage the contact point 83. A 20 ringing circuit for the gong 1 through the battery 74 will then be established as follows: from the battery 74 through the conductor 75, the conductor 34, the coil of the gong 1, the conductor 39, the armature 79, 25 contact point 83, conductor 80, conductor 76 to the battery 74. This circuit being closed, the gong will continue to ring until said circuit is broken. To break said circuit and restore the parts in the outer housing to 30 normal condition, the magnet 86 is energized from the middle battery 25 in the protected housing, by closing the circuit with a push button 84. The circuit which energizes the magnet 86 is then traced from 35 the battery 25 through the conductor 36, conductor 87, coils of the magnet 86, the conductor 85, push button 84, conductor 37 to the other side of the battery 25.

It will be seen that the batteries within 40 the vault are four in number and consist of the three open circuit batteries, 24, 25 and 26, and the closed circuit battery 27. A greater or less number of these batteries might be employed. As here shown the 45 battery 24, which I have called the upper battery, furnishes the current for ringing the gong under the right-hand shield 8. It also furnishes the current for ringing the right-hand test bell of the switchboard 50 when a general alarm is sounded, and a current for operating the drops when the vault protection, or the outside housing protection, is short circuited, or when the protection of the right-hand shield 8 is disturbed. 55 The battery 26, herein designated the lower battery, furnishes the current for ringing the gong under the left-hand shield 9, and the left-hand test bell 53, in case of a general alarm, and also for operating the 60 drops when the protection of the left-hand shield is disturbed.

The battery 25, referred to herein as the middle battery, furnishes the current for operating the outside alarm gong 1 in the 65 event of a general alarm, unless the cable

leading to the outside alarm has been severed. If the cable has been severed the outside gong 1 will ring from the local battery within the outside housing, the relay of the local circuit through the battery being 70 tripped by the cutting of the closed circuit in the cable. The middle battery also furnishes current for energizing the magnet or relay 86, for the purpose of resetting the drop or shutter 79, in case the local outside battery circuit is closed by the opening of the closed circuit in testing or otherwise. 75

The battery 27 furnishes the current for the closed circuit which extends through the cable to the outside alarm and serves to hold 80 the relay of this alarm normally out of action. In case this closed circuit is opened, either by cutting of the cable or otherwise, the outside relay is brought into action to close the local circuit through the battery, and the outside gong 1 in the protected housing, thus ringing the gong notwithstanding the severing of the cable. 85

The circuit from the middle battery that is closed by the middle drop and extends 90 directly to the gong 1 in the protected housing, I designate the "main ringing circuit." The circuits from the upper and lower batteries through the right and left-hand drops to the gongs under the shields 8 and 9, I 95 designate the "shield gong ringing circuits," and to distinguish one from the other, I refer to them as the right and left-hand shield gong ringing circuits. The circuits connected with the upper and lower batteries and extending from the protective devices of the vault, or the protected housing, and all of which are kept normally open by suitable barriers, and any one of which, when closed, causes the tripping of either 100 the right or the left-hand drop, and then of the central drop, and thereby the closing of the main ringing circuit, and also of the right and left-hand shield gong ringing circuits, I designate "tripping circuits" as the 110 action of each of these circuits is to operate one of the drops and thereby to cause the sounding of a general alarm. 115

I claim as my invention:

1. An electrical burglar alarm system, 115 comprising, in combination, a guarded structure having, in its inclosing walls, suitable electrical conductors insulated from each other, a protected housing having inclosing walls comprising electrical conductors insulated from each other, a main alarm located in said protected housing, a suitable battery arranged within said guarded structure, an open ringing circuit, connecting said main alarm with said battery, open tripping circuits connected with the insulated conductors of the guarded structure and protected housing, an automatic drop within the guarded structure arranged to be operated 120 when any one of said tripping circuits is 125 130

closed by electrically connecting the insulated conductors of the guarded structure or protected housing, and, when thus operated, closing said ringing circuit, a local alarm circuit arranged in said protected housing and including said main alarm, and a closed circuit extending from the guarded structure to the protected housing, and operating, when broken, to close the local alarm circuit in the protected housing.

2. An electrical burglar alarm system, comprising, in combination, a guarded structure having, in its inclosing walls, suitable electrical conductors insulated from each other, a protected housing having inclosing walls comprising electrical conductors insulated from each other, a main alarm located in said protected housing, a suitable battery arranged within said guarded structure, an open ringing circuit connecting said main alarm with said battery, a protected alarm located on the outer wall of said guarded structure, an open ringing circuit connecting said alarm with said battery, open tripping circuits connected with the insulated conductors of the guarded structure and protected housing, automatic drops within the guarded structure arranged to be operated when any of said tripping circuits is closed, and when thus operated closing said ringing circuits, a local alarm circuit arranged in said protected housing and including said main alarm and a closed circuit extending from the guarded structure to the protected housing and operating, when broken, to close the local alarm circuit in the protected housing.

3. An electrical burglar alarm system,

comprising, in combination, a guarded structure having, in its inclosing walls, suitable electrical conductors insulated from each other, a protected housing having inclosing walls comprising electrical conductors insulated from each other, a main alarm located in said protected housing, a suitable battery arranged within said guarded structure, an open ringing circuit connecting said main alarm with said battery, open tripping circuits connected with the insulated conductors of the guarded structure and protected housing, an automatic drop within the guarded structure arranged to be operated when anyone of said tripping circuits is closed by electrically connecting the insulated conductors of the guarded structure or protected housing, and, when thus operated, closing said ringing circuit, a local alarm circuit arranged in said protected housing and including said main alarm, a magnet in said protected housing provided with an armature that serves, when released from the magnet, as a circuit closer for said local alarm circuit, a closed main circuit, including said magnet, and extending from the guarded structure to the protected housing and serving normally to hold said armature out of circuit closing contact, and a battery in the guarded structure to which said closed main circuit is connected, substantially as described.

In witness whereof, I have hereunto set my hand this 7th day of August 1909.

WALTER K. COOK.
